UNITED STATES PATENT OFFICE.

HARRY L. RILEY, OF ATLANTIC CITY, NEW JERSEY.

ICE-CREEPER FOR HORSESHOES.

1,223,832.

Specification of Letters Patent. Patented Apr. 24, 1917.

Application filed November 6, 1916. Serial No. 129,648.

To all whom it may concern:

Be it known that I, HARRY L. RILEY, a citizen of the United States, residing at Atlantic City, in the county of Atlantic and

5 State of New Jersey, have invented certain new and useful Improvements in Ice-Creepers for Horseshoes, of which the following is a specification.

My invention has relation to ice-creepers 10 for horse-shoes.

In the carrying out of my invention, the principal object is to provide an ice-creeper of certain improved constructive arrangement, whereby the same can be quickly and 15 efficiently slipped onto and clamped to any size horse-shoe and occupying position at the toe portion only of the shoe; and a further object of my invention is to provide an ice-creeper in which securing to the horse-shoe 20 is accomplished by simple manipulation of the calk-members to clamp the same to the shoe as well as serving in application to the shoe, as the creeper.

My invention stated in general terms, 25 consists of an ice-creeper constructively arranged in substantially the manner herein-after described and claimed.

The nature and scope of my present invention will be more fully understood from 30 the following description taken in connection with the accompanying drawings forming part hereof, in which—

Figure 1, is a bottom plan view of a horse-shoe with an ice-creeper, embodying main 35 features of my invention, in one form, in this instance, consisting of two hinged members and with the creeper-plate slipped onto and firmly clamped to the toe portion of the shoe by means of set-screws and the calking-members.

Fig. 2, is a side elevation of the creeper-plate applied to the shoe and showing one of the toe calk-members and set-screws of the said creeper-plate of Fig. 1.

45 Fig. 3, is a transverse sectional view of the creeper on the lines 3—3 of Fig. 1, showing the creeper-plate and one of the calking-members of the creeper-plate, partly in elevation and partly in section, and the movable pin fitting the calking-member with its cup-shaped end for biting into the shoe surface, thereby to securely hold the creeper-plate 50 in firm position on the shoe.

Fig. 4, is a bottom plan view of a horse-shoe with a modified arrangement of the 55 creeper-plate, in this instance, a single-piece applied thereto.

Fig. 5, is a side elevation of Fig. 4; and

Fig. 6, is a vertical section of one of the creeper calking-members and loose pin 60 thereof, with its cup-shaped extremity removably fitting the shank of said member.

Referring to the drawings *a*, is the horse-shoe provided with a depending toe-piece *a*¹, and projecting heel-pieces *a*² and *a*³. The 65 horse's hoof *a*⁴ in Figs. 2 and 4, is illustrated in dotted outline fitted to the shoe *a*, and showing the rear arch *a*⁵, of the horse's hoof as it spans the side-members of the shoe.

The creeper-plate *b*, in Fig. 1, consists of 70 two hinged members and the body is formed with a circular channel *b*¹ and with preferably one overlapping wall beveled to form a flange *b*². The said plate being readily slipped onto the surface of the shoe from the 75 rear of the same, as clearly shown in Figs. 1 and 2, and also so that when the said flange is actually in operative engagement with the shoe *a*, from the inner side thereof, the arch of the horse's hoof will come practically up 80 against the top surface of the flange *b*², as clearly shown in Figs. 2 and 4. The bottom member of the creeper-plate *b*, is extended well onto the bottom side of the horse-shoe *a*, as in Figs. 1 and 4, and in which are in- 85

serted the calking and clamping members *c* and set screws *c*¹. The calking members, each consists of preferably a coned shaped flange device *c*, with threaded hollow shanks *c*², extending through perforations provided 90 in the bottom of the creeper-plate *b*. In the hollow of the shank, is mounted a loose-pin *c*³, with a cup-shaped extremity *c*⁴, to bite into the under shoe-surface, as in Fig. 3, so as to securely clamp the creeper-plate *b*, to 95 the shoe *a*, and against movement; the shank *c*², of the creeper *b*, while entering the said plate does not bear in normal position against the shoe-surface, but only the loose-pin *c*³, into the hollow of the said shank, as 100 illustrated in Fig. 3, whereby possible unthreading of the creeper is avoided or the creeper-plate *b* becoming loose, dropping off or slipping from its position on the shoe. By the forming of each of the calking- 105 devices *c*, with a polygonal flange *c*⁵, is pro-

vided thereby, a ready means for the application of a wrench thereto to quickly and efficiently release the creeper-plate *b*, from the shoe *a*, or to more securely tighten the 5 same to the shoe *a*, as occasion may require.

In Figs. 4 to 6, inclusive, the ice-creeper plate *b*, is made in a single piece rather than in two hinged parts as in Figs. 1 and 3. In 10 all other respects the said creeper-plate *b*, in arrangement and application to the shoe is the same, as hereinbefore fully described.

Having thus described the nature and objects of my invention what I claim as new and desire to secure by Letters Patent is:—

15 1. The combination with a horse-shoe, of an ice-creeper, consisting of a channelled plate, one wall formed into an overlapping beveled flange adapted to be slipped onto the shoe-surface from the inner side, a calking-device having a hollow threaded shank flanged intermediate of both ends, a movable pin fitting the body of said device, the shank of said device adapted to enter said creeper-plate and the said pin to bite into the said 20 shoe-surface to prevent loosening, slipping or disarrangement of said creeper-plate in position and forming with said creeper-plate flange and set-screw the securing means 25

for said plate with said shoe-surface, substantially as described.

2. The combination with a horse-shoe, of an ice-creeper, consisting of an angular channelled hinged two-part plate, one wall formed into an overlapping beveled flange adapted to be slipped onto the shoe-surface 30 from the inner side and calking-devices having hollow threaded shanks flanged intermediate of both ends and with pins fitting the bodies of said devices, the shanks of said devices adapted to enter said creeper-plate and said pins to bite into the shoe-surface to prevent loosening, slipping or disarrangement 35 of the creeper-plates in position and forming in conjunction with the creeper-plate flange and set-screws the securing means for the creeper-plates with said shoe-surface, substantially as and for the purposes described.

In witness whereof, I have hereunto set my signature in the presence of two subscribing witnesses.

HARRY L. RILEY.
